UNITED STATES PATENT OFFICE.

HENRY W. STOCKING, OF AVALON, CALIFORNIA.

TACKLE-BLOCK.

SPECIFICATION forming part of Letters Patent No. 739,119, dated September 15, 1903.

Application filed February 4, 1903. Serial No. 141,936. (No model.)

To all whom it may concern:

Be it known that I, HENRY W. STOCKING, of Avalon, in the county of Los Angeles and State of California, have invented new and useful Improvements in Tackle-Blocks, of which the following is a specification.

My invention consists in providing self-locking means for tackle-blocks; and the object is to provide a tackle-block which will automatically lock itself when the operator slackens on the rope to which the weight being raised is attached. I accomplish this object by means of the device herein described, and shown in the accompanying drawings, in

15 which—

Figure 1 is a side elevation of a tackle-block embodying my invention. Fig. 2 is a side elevation, partly broken away. Fig. 3 is an edge view. Fig. 4 is a fragmentary view of

20 the strap A, showing the slot A' therein.

In the drawings, A is the side straps of the block, in each of which is a slot A' for the reception of the projecting ends of the main sheave B, which carries the rope D. The configuration of the slot is shown in Fig. 4. It has an upper and a lower resting-seat a and a', respectively, for the supporting projecting ends of the axle C, the purpose being to form a firm support for the sheave B while in its elevated position, as shown in Fig. 1, and a firm support while in the depressed position. (Shown in Fig. 2.) When the sheave is in its elevated position, (shown in Fig. 1,) it will have crowded the rope D up against the periphery 25 of the eccentrically-mounted sheave or cam-roller F and locked the rope against movement in direction of the end D'', on which the weight is attached, and will securely hold the same in this position and prevent the weight

40 secured to this end from falling. This condition will result whenever the force (which is applied by the hand to the end D' of the rope in elevating the weight attached to the other end) is removed. When the D' end of 45 the rope is released, the springs G, mounted on the outside of the straps A, will throw the axle C out of the lower seat a' into the upper seat a. This upward movement of the axle will carry with it the cam-actuating arm H, 50 loosely mounted at its lower end on the axle C and pivotally mounted on the cam-roller F, close to the periphery thereof. In moving up

with the axle it will cause the cam-roller to swing from the position shown in Fig. 2 (which is the position of the sheave A and the cam-roller F when power is applied to the D' end of the rope) into the position shown in Fig. 1, being the locked, or elevated position of the sheave A and the depressed or locked position of the cam-roller when the power is removed 55 from the D' end of the rope. When power is applied to the end D' of the rope, the pressure thereon will overcome the tension of the spring G, which is to hold the sheave in its elevated locked position, as in Fig. 1, and to bring the 60 sheave down into its depressed operative position, as shown in Fig. 2, the cam-actuating arm H meanwhile carrying the cam-wheel into its elevated and unlocked position. (Shown in Fig. 2.)

Having described my invention, what I claim as new, and desire to secure by Letters Patent, is—

1. The herein-described automatically-locking tackle-block, comprising a main sheave 75 revolvably mounted in side straps, the axle of the sheave projecting through slots in the side straps; side straps having composite slots therein, the said slots having two axle-supporting seats, one seat being disposed 80 above the other, the axle of the main sheave adapted to project into and through said slot and engage springs on the outside of the side straps; axle-engaging springs on the side of the straps adapted to throw the axle of the 85 sheave into the upper seat in the slot; a cam-roller above the main sheave journaled in bearings in the side straps; an arm pivoted at its upper end on the side of the cam-roller close to the periphery thereof, the lower end 90 of the arm revolvably mounted on the axle of the main sheave.

2. A tackle-block, comprising a sheave-frame; a main rope-carrying sheave revolvably mounted therein having an axle projecting 95 on both sides thereof through a composite slot in the sides of the frame, the said slots each having two axle-supporting seats, one disposed above the other; a cam-roller revolvably mounted in said frame above the main 100 sheave, the cam-roller having pivoted on the side thereof an actuating-arm; an actuating-arm revolvably mounted at one end on the axle of the main sheave and the other end pivot-

ed to the cam-roller; springs on the outside of the frame adapted to engage the projecting ends of the axle of the main sheave and to crowd the same into the upper seats in the slot and hold the same therein.

3. The herein-described self-locking tackle-block comprising the side straps A, having therein in each strap a slot A', the slot being provided with two axle-supporting seats *a* and *a'*; a main sheave B revolvably mounted in and between said side straps, and having axle C projecting on each side thereof; a cam-roller F revolvably mounted in said side straps above said sheave; a cam-roller - actuating arm H loosely mounted on said axle at one end and pivoted at the other end on the cam-

roller close to the periphery thereof; springs G mounted on the outer side of the side straps and adapted to bear against the projecting ends of said axle and to crowd the same down ²⁰ and into the upper seat *a* in the slot.

4. In a tackle-block of the character described side straps having composite slots with two axle-supporting seats therein.

In witness that I claim the foregoing I have ²⁵ hereunto subscribed my name this 23d day of January, 1903.

HENRY W. STOCKING.
